WIRING FIXTURE

Howard W. Garbe, Hinsdale, and Herman Saravalli, Chicago, Ill., assignors to Western Electric Company, Incorporated, New York, N. Y., a corporation of New York

Application January 11, 1940, Serial No. 313,403

1 Claim. (Cl. 29—89)

This invention relates to a wiring fixture and more particularly to a wiring fixture for holding a plurality of wires in engagement with terminals to which the wires are to be fixed.

An object of the present invention is to facilitate the wiring of electrical apparatus.

In accordance with one embodiment of the invention as applied to the wiring of telephone cross bar switch assemblies, there is provided a fixture adapted to be mounted between the terminals of a cross bar switch assembly to hold the terminals in a predetermined position and force strap wires, which are to be secured to the terminals, into intimate engagement with the terminals. The apparatus provided comprises a bar having a series of slots therein for receiving the tips of the terminals and holding the terminals apart during the soldering thereof. Fixed to the bar are a plurality of spring pressed members, one being provided between adjacent rows of terminals for holding the wires in intimate contact with the terminals during the soldering of the wires to the terminals.

A better understanding of the invention will be had by reference to the following specification when considered in conjunction with the accompanying drawing, wherein

Fig. 1 is a plan view of the apparatus embodying the invention;

Fig. 2 is a front elevational view of the apparatus shown in Fig. 1;

Fig. 3 is a front elevational view on a reduced scale of the apparatus shown in Figs. 1 and 2 mounted on a cross bar switch assembly;

Fig. 4 is an enlarged fragmentary sectional view taken along the lines 4—4 of Fig. 3 in the direction of the arrows, showing the details of construction of the apparatus, and

Fig. 5 is a fragmentary sectional view taken on the line 5—5 of Fig. 4 in the direction of the arrows.

Referring to the drawing, wherein like reference characters designate the same parts throughout the several views, a hold down fixture embodying the present invention comprises a relatively long bar 10, which, as shown most clearly in Figs. 4 and 5, comprises a main body portion 11, which is slotted throughout its length, as shown at 12, to receive a serrated bar 13. The bar 10 has a projection 14 formed thereon, which is of sufficient thickness to fit tightly between adjacent rows of terminals 15 on a cross

bar switch assembly. The projection 14 is pointed at its edge, as shown at 16, to render it easier to insert the projection 14 between the rows of terminals. As shown most clearly in Fig. 4, the serrated member 13 fits into the slot 12 and is held in place on the bar 10 by means of screws 17, which extend substantially all the way through the bar 10, thereby to hold the serrated bar 13 securely in the bar 10.

10. The serrated bar 13 has a plurality of slots 18 (Figs. 1 and 5) cut therein of sufficient width to receive the terminals 15 and these slots are widened, as shown at 19—19, to guide any terminals 15, which are bent slightly out of alignment, into the proper position with respect one to another. It will thus be apparent that a bar 10 of the type just described, having the serrated bar 13 mounted thereon, will, when slipped into engagement with the terminals of a piece of electrical apparatus, for example, a cross bar switch assembly, hold the terminals of the apparatus spaced equally from each other in a horizontal plane.

20. Fixed to the left edge (Fig. 4) of the bar 10, by means of screws 21—21, are a series of substantially L-shaped springs 22, which are spaced along the bar 10 so that when the bar 10 is positioned on a row of terminals on a cross bar switch assembly, there will be one spring 22 positioned between each adjacent bank of terminals. These springs 22 have loosely mounted at their free end a hold down bar 23, which is adapted to engage a series of wires 24 strung above the terminals 15 and force the wires down into intimate engagement with the terminals. The hold down bar 23 is loosely mounted on the free end of the spring 22 in order that it may automatically compensate for any irregularities in the tension of the wires 24.

25. The fixture hereinbefore described is particularly useful for holding strap wires 24 in engagement with the terminals of the cross bar switch assembly, a fragment of which is shown in Fig. 3. These assemblies comprise end frames 30 and 31 between which units of switching apparatus are positioned. These units comprise a supporting plate 32 and other equipment, which equipment has rows of terminals 15 extending from it. In the manufacture of cross bar switch assemblies, it is necessary to connect one terminal of each group of terminals to the corresponding terminal of every other group on the same level with them and in doing this, an operator, after having arranged a plurality of wires across the cross bar switch assembly in any suitable man-

ner, for example, by stretching the wires around suitably supported pins 33, may hold all the wires in a single row in intimate engagement with their associated terminals by simply sliding the projection 16 between adjacent rows of terminals 15. The terminals, of course, will enter the slots 18 and be held in the proper position horizontally.

Although a specific embodiment of the invention has been described hereinbefore, as designed for use in connection with a specific form of apparatus, it will be understood that modifications of the apparatus might be made to render it useful in connection with other equipment to be similarly wired without departing from the scope of the appended claim.

What is claimed is:

A wiring fixture comprising a terminal engaging bar adapted to engage the edges of a row of terminals, a spring pressed member mounted on said bar, a hold down bar pivotally mounted on the free end of the spring for forcing wires into engagement with the opposite edges of said row of terminals, and spacing means mounted on the bar between the spring pressed member and the bar for properly positioning the terminals, said spacing means comprising a serrated member having the teeth thereof pointed to guide the terminals to position.

HOWARD W. GARBE,
HERMAN SARAVALLI.
